UNITED STATES PATENT OFFICE.

CHARLES W. GREEN, OF ILION, NEW YORK, ASSIGNOR TO REMINGTON ARMS COMPANY, INC., A CORPORATION OF DELAWARE.

CASH REGISTER.

Application filed March 14, 1925. Serial No. 15,498.

This invention relates to printing attachments for cash registers and has for its object the provision of a device to prevent improper operations of the printing mechanism which results in fraudulent impressions upon a record bearing material.

This particular device is shown as applied to a type of machine, the general principles of which are disclosed in the U. S. application, Ser. No. 263,125 filed November 19, 1918, by Frederick L. Fuller, as well as British Patents #135,465—157,823—157,824—157,825 granted for the same invention, although from a consideration of the nature of these improvements it will be obvious to those skilled in the art that this device may be applied to various other types of machines.

With these and incidental objects in view, the invention consists in certain novel features of construction and combinations of parts, the essential elements of which are set forth in the appended claims and a preferred form of embodiment of which is hereinafter specifically described with reference to the drawings which accompany and form part of this specification.

Of said drawings:

Fig. 1 is a cross sectional view of the cash register showing a part of the platen operating means and a portion of the paper strip feeding devices.

Fig. 2 is a cross sectional view of the register taken substantially through the center of the machine and shows the driving means for the revolution shaft, the differential devices for adjusting the type carriers, and the platen operating means in combination with associated locking devices.

Figs. 3 and 4 are views in elevation similar to Fig. 2 showing the platen operating devices and associated locking devices in various operated positions.

Fig. 5 is an end view of the printer showing the co-operating locking devices.

The various parts of the mechanism are supported by a suitable frame work and are enclosed by a cabinet 20 which may be made of any desired material. As shown in Fig. 1 there is hinged to the cabinet, lids 21 and 22 which are controlled by locks so as to permit different persons to have access to the mechanisms. The flat lid 21 has attached thereto a glass 23 through which may be viewed the record strip upon which the items are printed.

Lifting of the lid 21 will give access to the

paper holding devices so that the supply of paper may be replenished at will.

The illustrative machine is provided with a number of keys divided into groups, one of the keys being indicated by reference character 24. Each key lever 24 is pivoted upon a shaft 25 and resting upon the rear ends of the keys is a key coupler journalled at 26 between the side frames and provided with a nose 27 co-operating with notches 28 formed in the rear ends of the operating keys. When the outer ends of the keys are depressed the key coupler is rocked clockwise and the nose 27 enters the notches 28. The purpose of such key coupler mechanisms is well known in the art and need not be discussed herein in detail.

Connected to the key coupler at 29 is a vertical reciprocating rack plate 30 provided with oppositely facing rack teeth 31 which alternately mesh with a gear 32 fast to the main operating shaft 33. The arrangement of this mechanism is such that a reciprocation of the key coupler 25 by the keys will effect a complete rotation of the gear and the shaft 33 to which the gear is secured. This mechanism is also well known in the art and shown in many patents and one form which this mechanism might take is illustrated in detail in the patent to Thomas Carney, #482,461 granted September 6, 1892.

The differential mechanisms or devices controlled by the various groups of keys for adjusting the item type carriers are all similar in construction and principle and a description of one will suffice for all. As shown in Fig. 2 the amount key 24 is provided with an upwardly extending arm 34 carrying a suitable anti-friction roller 35 co-operating with a differential slot formed in a cam plate 36. Loosely mounted upon a transverse shaft 37 is a frame 39 provided with spaced slots in which are secured by pins 38 a series of these cam plates, one for each key. The cam plates 36 are provided with L shaped slots 40 and 41, the slots 40 being concentric with respect to the shaft 37. The slots 41 are, however, graduated so that when the roller 35 carried by the arm 34 of a depressed key operates in a cam slot 41 of its associated cam plate 36 it will move the frame 39 differentially and to an amount commensurate with the value of the key depressed. When, however, the frame 39 is operated by the depression of a key 24 of a certain group the rollers 35

of the undepressed keys of the same group will play in the arcuate slots 40 of their respective cam plates 36 thereby permitting the frame 39 to be raised differentially without interfering with the rollers 35 of the unoperated keys.

It is to be understood that there is a differential frame for each group of amount keys. As is shown in the drawing the differential frame 39 has attached thereto a segmental rack 42. In continuous mesh with the teeth of the segmental rack 42 is a pinion 421 (Fig. 1) attached to an item type wheel 43 mounted upon the shaft 44. From the above it will be evident since there may be nine keys in a particular group and a corresponding number of cam plates 36 the type carrier 43 may be brought to any one of the nine different positions by the depression of a key 24 associated with such group of keys. In a manner similar to this the keys associated with any of the denominational groups will adjust their associated type carriers so that when printing is effected the type wheels will print characters upon the record strip corresponding to the value of the keys depressed.

Record strip printing mechanism.

30 It is desirable each time an item is entered in the machine that this amount be printed on the record strip so that there may be a complete record of all the transactions entered in the machine. At the end of an arbitrary period the record strip may be detached from the supply roll and filed away for future reference.

40 The printing mechanism for printing the items comprises a printing frame formed of two side plates 45 and 46, the lower ends of which are provided with claws 47 overlying the shaft 37. Normally the printing mechanism rests by its own weight in the position shown with lugs 48 contacting with a portion of the back frame 49. The side frames 45 and 46 are connected together by a cross member 50 and shafts and other members which will be referred to hereinafter.

50 Journalled in the printer side plates 45 and 46 is a shaft 51, the extreme left end of which has fastened to it a bell-crank 52 carrying a roller which coacts with the race of a box cam 53 (Fig. 1) fast to the shaft 33. As has been mentioned hereinbefore the shaft 33 is given a complete rotation during each operation of the machine and the rotation of the box cam will rock the shaft 51 to actuate a platen and to feed the record strip.

60 Extending transversely of the printer side frames 45 and 46 is a platen supporting shaft 54 upon which is supported a platen 55 by means of forwardly extending arms 56 and 57. The under face of the platen 55 is provided with a rubber impression block 58.

55 Extending rearwardly from and integral

with the right arm 57 is an arm 59 to which is pinned at 60 a platen operating arm 61. For actuating the platen operating arm 61, there is provided a hammer 62 which is formed as part of an arm 63 pivoted to the inside right printer side frame 46 by a stud 64. The hammer 62 is forced upwardly by a spring 65 bearing at its lower end against a lug 66 carried by the right printer frame 46. The arm 61 is furthermore provided with a spring-pressed retracting pawl 67 having a tail 68 bearing against an adjustable stop such as a set-screw 69 passing through a lug 70 integral with the hammer arm 63. The pawl 67 is furthermore provided with a lug 71 co-operating with a nose 72 formed as part of an arm 73 secured to the main printer operating shaft 51.

70 It will be obvious that when the arm 73 is rocked clockwise by means of the bell-crank 52 and the shaft 51 to which the bell-crank is secured, the nose 72 will bear against the lug 71 of the pawl 67 and retract the hammer 62 against the tension of the spring 65. Upon a further movement of the arm 73 (Fig. 4) the nose 72 will clear the lug 71 and permit the hammer portion 62 to strike a projection from the operating arm 61 and rock the platen 55 downwardly about its pivot 54 to effect a printing impression from the adjusted type carriers.

75 It will be noted that as shown in Fig. 2 the rearward end of the operating arm 61 is normally (Fig. 2) held against any movement by means of a lug 74 integral with the arm 73 and a stud 75 attached to the printer side frame 46. This prevents the platen 55 from dropping downwardly by virtue of its weight and holds it up to permit feeding of the inking ribbon and record strip. The upper edge 76 of the platen operating arm 61 is substantially concentric with respect to the shaft 51 but is provided with a cut-away portion or drop 77 which permits the platen arm 61 to be rocked by the hammer 62 without interference with the lug 74 of the arm 73.

80 The record strip 78 (Fig. 1) upon which the items are printed is drawn from a supply roll 79 and passes over a fixed roller 80, over a second roller 81, hence forward and over the platen 55, over a roller 82, and finally to the storage roll 83. None of the details of the strip feeding devices will be described inasmuch as they form no part of the present invention and all that need be said about these devices is that they function in such a manner so as to feed the paper strip an increment between printing operations.

85 The inking ribbon 84 (Fig. 2) and the means for shifting it also form no part of the present invention and any suitable form or construction well known in the art may be utilized.

90 As shown in Fig. 1, the lid 21 is provided with a glass 23 provided with an open-

- ing 85 permitting the clerk to enter written notations adjacent each printed transaction. Inasmuch as some written notations are of an extent requiring more space than is usually provided a special lever is provided for advancing the paper strip whenever desired. To this end a spacing lever 861 (Fig. 1) extends through a slot in the lid 21 to permit its external operation and it has pivoted at its lower end a paper feeding pawl 871 co-operating with a ratchet wheel 880 fast to the storage roll 83. By the manipulation of this lever the paper may be fed as many spaces as desired.
- 15 The lid 21 is controlled by a lock, the key of which is usually retained by the clerk or other authorized person to permit access to the paper supply devices, etc. This has laid the machine open to improper manipulation
- 20 by permitting the operator after opening the lid to strike the platen 55 a sharp blow and print either a line of zeroes from the normally adjusted type carriers or other values from the partially adjusted type elements.
- 25 It will be noted that the platen 55 is normally held from movement by the lug 74 and pin 75 but these locking members are located some distance from the shaft 54 on which the platen is pivoted. In some registers it is
- 30 therefore possible to give the platen such a sudden blow that the arm 61 will bend or give sufficiently to allow the platen to strike the type wheels which are in close proximity. Where dimensions are not strictly adhered to
- 35 during manufacturing processes sufficient play may exist between the co-operating locking members to permit the platen to be improperly operated without even flexing the arm 61 or other connected parts.
- 40 In order to make it clearer how the register can be operated improperly it will be assumed for the sake of example, that a \$9.00 transaction is to be registered. The appropriate key will then be depressed and during
- 45 the time that the dollars type wheel is being adjusted to bring it to the "nine" position, the platen may be struck a blow and print \$6.00, for example, upon the record strip. By holding the \$9.00 key in its partially operated position and then operating the spacing lever 861 a fresh portion of the record strip can be brought over the type carriers. The operation of the key may then be completed and this will allow the printing of the
- 55 proper amount upon the record strip in the usual manner. The improper operation of the platen and subsequent advancement of the paper strip produces a double record for a single transaction, thus of course, producing a false entry in the machine. To prevent such manipulation means have been provided to positively lock the platen and unlock it just prior to the time it is intended to be operated, the time during which it is unlocked being so brief that no time will be

given to operate the machine in the fraudulent manner just described.

It will be noted in Fig. 5 that there is attached to one end of the platen 55 a plate 86 normally co-operating with a locking arm 87 ⁷⁰ loosely mounted upon the shaft 44 and having a pin and slot connection at its lower end to a member 88, the forward end of the member passing through a slot 881 in a guide plate 882 (Fig. 3) attached to the frame of ⁷⁵ the machine. The rear end of the member 88 is urged upwardly by a compression spring 89 so that its lug 90 contacts with a lug 91 which is formed as part of a plate 92 screwed to the lug 70 which, it will be remembered, is integral with the arm 63. The member 88 is provided with an L shaped slot 93 co-operating with a stud 94 attached to part of the machine frame. A spring 95 draws the member 88 rearwardly so that the ⁸⁵ locking arm 87 is normally in the position shown in Fig. 2 wherein it will be seen that in view of its locking relationship with the plate 83 it positively locks the platen 55 so as to prevent its downward movement by the application of a sudden blow.

When it is desired to operate the machine and print the amount of the transaction upon the record strip, it is necessary to disable the locking means so as to permit the platen to ⁹⁵ be operated. The manner in which this is performed will now be described in detail, reference being had particularly to Figs. 3 and 4.

When the machine is operated the shaft 33 ¹⁰⁰ will be rotated and through the box cam 53 and bell-crank 52 the shaft 51 will be rocked clockwise as viewed in Fig. 3 and by means of the nose 72 on the arm 73 and co-acting pawl 67 will force the arm 63 downwardly as has been premised hereinbefore. Since the lug 91, carried downwardly with the arm 63, co-operates with the lug 90 on member 88, it will force the rear end of the member 88 downwardly. Upon a further downward ¹¹⁰ movement of the hammer 62 the lug 91 will clear the lug 90 and due to the compression stored in the spring 89 the rear end of the member 88 will again be raised bringing the parts to the position shown in Fig. 3, wherein ¹¹⁵ it will be noted that the lug 91 occupies a position just to the rear of the lug 90, the platen still being locked.

As the arm 73 continues its clockwise movement the nose 72 will clear the retracting pawl 67 and due to the compression stored in the hammer operating spring 65 the arm 63 will be raised quickly and since the lug 91, carried up with the arm 63, is just behind the lug 90 it will force the member 88 slightly ¹²⁰ forwardly rocking the locking arm 87 counter-clockwise to the position shown in Fig. 4. In this position of the parts it will be noted that the platen is now unlocked for operation, but the hammer 62 has not yet contacted with ¹²⁵ ¹³⁰

the platen operating arm 61. Upon the continued upward movement of the hammer 62 the platen operating arm 61 will be struck thereby rocking the platen 55 to take an impression from the adjusted type carriers. At this time the lug 91 will have been lifted above the lug 90 so that the spring 95 may draw the member 88 rearwardly again to once more bring the locking arm 87 into co-operative relation with the plate 86 on the platen.

As the arm 73 is now restored to its normal position to again bring the parts to the position shown in Fig. 2, the hammer and the member 88 will not be disturbed since the rear face of projection 72 will merely rock the retracting pawl 67 idly about its pivot. It will be noted that from the time that the lugs 90 and 91 clear each other to the time that the printing operation is performed and the member 88 is again restored the movement of the parts is performed so quickly as to allow no time for the operator to improperly operate the various parts of the mechanism to produce a false entry in the manner hereinbefore described.

While the form of the mechanism herein shown and described is admirably adapted to fulfill the objects primarily stated, it is to be understood that it is the desire not to confine the invention to the one form of embodiment shown and described as it is susceptible of embodiment in various forms all coming within the scope of the claims which follow.

35 What is claimed is:—

1. In a cash register, the combination of a platen, means for operating the latter, devices for normally locking it against operation and connections from said operating means for disabling said locking means.

40 2. In a cash register, the combination of a pivoted platen, a plurality of locking devices for normally locking it against operation and an operating mechanism having connections for disabling all the locking devices.

45 3. In a cash register, the combination of a pivoted platen, a plurality of locking devices located on opposite sides of the pivotal point of the platen for normally locking it against operation, and an operating mechanism having connection for disabling all the locking devices.

50 4. In a cash register, the combination of a pivoted platen, means for rocking it downwardly to effect printing impressions, means for normally locking it against movement and connections whereby the first said means causes unlocking of the platen preliminarily to rocking the latter to printing position.

55 60 5. In a cash register, the combination of a platen, a locking member co-operating with said platen and normally locking the same against movement, an operating mechanism, and means under control of the operating

mechanism for operating the locking member 65 to unlock the platen as a preliminary to actuation of the latter.

6. In a cash register, the combination of a platen, a locking arm normally co-operating with the platen, a member having a connection to said locking arm, an operating mechanism, and means under control of the operating mechanism to shift said member to operate the locking arm to unlock said platen.

7. In a cash register, the combination of a platen, a series of keys, type carriers, means under control of the keys for adjusting the type carriers and operating the platen, and a locking device for the platen controlled by the keys.

8. In a cash register, the combination of a platen, a series of keys, type carriers, means under control of the keys for adjusting the type carriers and operating the platen, and a locking device for the platen controlled by the keys and operated prior to the time the platen is operated.

9. In a cash register, the combination of a series of keys, type carriers, a differential mechanism under control of the keys for setting the type carriers, a pivoted platen co-operating with the type carriers, a hammer to drive the platen, and a locking device for the platen controlled by the hammer.

10. In a cash register, the combination of a platen, a hammer for operating the platen, and a locking device for the platen controlled by said hammer.

11. In a cash register, the combination of a platen, a locking device for the platen, a member movable with the platen, and a hammer having means to operate the locking device and said member.

12. In a cash register, the combination of a platen, a locking device for the platen, a member movable with the platen, and a hammer having means to operate the locking device first and then said member.

13. In a cash register, the combination of a pivoted platen, a locking device for the platen, a shiftable member having connections to the locking device, a hammer for the platen, and means operated by the hammer for shifting the said member.

14. In a cash register, the combination of a platen, a shaft, a set of type carriers mounted on said shaft and co-operating with the platen, and a locking device for the platen mounted upon said shaft.

15. In a cash register, the combination of a platen, a hammer, a member for retracting the hammer to permit it to operate the platen, and a pair of locking devices operated respectively by said hammer and said member.

16. In a cash register, the combination of a platen, a hammer for the platen, a locking device for the platen, a shiftable member for operating said locking device, and a member

carried by the hammer adapted to engage one end of the shiftable member to operate said locking device.

17. In a cash register, the combination of a platen, a hammer for the platen, a locking device for the platen, a shiftable member for operating said locking device, and a hammer adapted to first engage one end of the shiftable member to operate said locking device 10 and to then operate the platen.

18. In a cash register, the combination of a platen, a locking device for the platen, a shiftable member for operating said locking device, a hammer adapted to first engage one 15 end of the shiftable member to operate said locking device and to then operate the platen, and spring means to return the locking device to normal locking position.

19. In a cash register, the combination of a platen, a locking device for the platen, spring 20 means for normally holding the locking device in its locking position, and a hammer for first operating the locking device and then the platen.

20. In a machine of the class described, an impression platen, a hammer for operating said platen, means for moving said hammer against the action of a spring and then releasing it for driving action by the spring, a lock normally preventing movement of said platen, means for disabling said lock, and connections between said last mentioned means and said hammer whereby said means is operated to release the platen during the spring driven movement of the hammer. 25 35

21. In a machine of the class described, an impression platen, a hammer for imparting a driving impulse to said platen, locking means normally preventing movement of said platen, a member controlling said locking means, and connections between said member and said hammer for releasing said locking means only during the platen driving movement of said hammer. 40 45

In witness whereof I have signed my name hereto this 12th day of March, 1925.

CHARLES W. GREEN.
